United States Patent Office

Des. 198,253
Patented May 19, 1964

198,253

RUG PAD OR SIMILAR ARTICLE

Irving R. Roth, Los Angeles, Calif., assignor to Oreco Industries, Inc., Los Angeles, Calif., a corporation of California

Filed Nov. 5, 1963, Ser. No. 77,292

Term of patent 14 years

(Cl. D92—4)

FIG. 1.

FIG. 2.

FIG. 3.

FIG. 4.

FIG. 5.

FIG. 6.

I claim:

The ornamental design for a rug pad or similar article, as shown.
